UNITED STATES PATENT OFFICE.

PAUL D. SULLIVAN, OF YONKERS, NEW YORK, ASSIGNOR TO FORSHEIM & KONIGSBERG, OF NEW YORK, N. Y., A FIRM.

DESIGN FOR A MEDALLION.

44,456.

Specification for Design.

Patented Aug. 5, 1913.

Application filed June 11, 1913. Serial No. 773,137. Term of patent 7 years.

To all whom it may concern:

Be it known that I, PAUL D. SULLIVAN, a citizen of the United States, and a resident of Yonkers, in the county of Westchester and State of New York, have invented a new, original, and ornamental Design for a Medallion, of which the following is a specification, reference being had to the accompanying drawing, forming part thereof.

The figure is a face view of a medallion illustrating my new design.

I claim:

The ornamental design for a medallion, as shown.

PAUL D. SULLIVAN.

Witnesses:

JACOB H. HIRSCH,

CLARENCE L. ELLERS.
